(57) **CLAIM**

The ornamental design for a vehicle bumper cover, shown and described.

DESCRIPTION

The vehicle front bumper cover is styled independently of adjacent vehicle panels. To the extent that any feature lines are illustrated, they are intended to illustrate the crest and valley of the feature and are not necessarily sharp bends in the part. Shading is used to illustrate the curvature of the part and not color. Areas shown in or bounded by broken lines are not claimed. Any functional features of the vehicle front cover bumper are not claimed. Views are orthogonal projections unless otherwise noted. The various views are not necessarily to scale in order to better illustrate the design.

FIG. 1 is a perspective view of a vehicle front cover;

FIG. 2 is a rear elevational view of the vehicle front bumper cover;

FIG. 3 is a front elevational view of the vehicle front bumper cover;

FIG. 4 is a right side elevational view of the vehicle front bumper cover, enlarged to show detail;

FIG. 5 is a left side elevational view of the vehicle front bumper cover, enlarged to show detail;

FIG. 6 is a top plan view of the vehicle front bumper cover; and,

FIG. 7 is bottom plan view of the vehicle front bumper cover.
